UNITED STATES PATENT OFFICE.

WALTER H. BATTS, OF GRAND RAPIDS, MICHIGAN.

SHIPPING BOX FOR CLOTHING.

Application filed June 1, 1926. Serial No. 112,783.

This invention relates to a shipping box for clothing wherein clothing may be placed on hangers and the hangers securely connected with an end or both ends of the box 5 so that no possibility of disengagement of the hangers can take place when the box is closed and sealed for shipment, but from which the hangers may be readily released when the box is opened after its destination 10 has been reached. It is a primary object and purpose of the present invention to provide a simple construction of this character which is strong, durable and efficient. The invention consists of many novel details of construction and arrangement of parts for effectively attaining the ends stated, as will be 15 fully apparent from the following description taken in connection with the accompanying drawings, in which—

20 Fig. 1 is a fragmentary perspective view showing the manner in which the hangers for the garments are releasably connected with the end of a box in which garments are held for shipping.

25 Fig. 2 is an enlarged fragmentary vertical section through the construction shown in Fig. 1.

30 Fig. 3 is a similar section, the box being in closed condition and the hangers locked in place against disengagement from the member with which they are connected.

35 Fig. 4 is a longitudinal vertical section through the shipping box, garments being connected with both ends thereof.

40 Fig. 5 is a fragmentary horizontal section through one end of the shipping box illustrating a slightly modified form of construction and one which is used when rounded suspension hooks for the garment hangers are used, and

45 Fig. 6 is a fragmentary transverse vertical section through the construction shown in Fig. 5 showing an inner end elevation of the shipping box.

Like reference characters refer to like parts in the several views of the drawings.

The box may be of any desired construction having a bottom 1, ends 2 and a top or cover 3 with the usual sides completing the 50 box and this box may be of any desired or required depth. While it is shown in the drawings as shallow and capable of containing but two suits at each end, the depth may be increased for additional suits of clothes as is obvious. The box shown is of paper board 55 but the material used to make the box is not

limited in any respect to paper board but any desired material may be used quite as well.

On the inner side of the ends of the box, 60 either one or both of said ends, a sheet metal supporting member is secured. This member is of channel form having a vertical web 4 from which flanges 5 are bent at right angles and from the edges of which flanges 65 outwardly turned sections 6 are bent, the same lying against the inner side of the end 2 of the box and through which rivets or other equivalent fastening means are passed to secure the sheet metal member rigidly to 70 and within the box, substantially midway between its sides. The web 4 is spaced a distance from the inner side of the end to which it is attached. A plurality of spaced apart 75 rectangular slots 7 are cut in the web and the metal which is struck therefrom at one side is formed into a grooved supporting hook 8 there being a space between the free edge of each hook part 8 and the upper edge of the slot 7 with which it is associated. 80

The hanger 9 which carries the garments may be of any desired form having a suspension hook 10. As shown in Figs. 1, 2 and 3 these hooks are of what is known as the square form and each terminates in an eye 85 loop 11 though with this type of hook the loop 11 has no function in connection with retaining the hangers in engagement with the parts 8. The upper horizontal section of the hook 10 passes freely through the 90 opening between the free edge of the hook part 8 and the adjacent upper edge of the slot 7 and may then be engaged with said hook support 8. Each of the members 8 may have a suspension hook 10 of a garment 95 hanger 9 connected therewith.

When the box is filled in order to hold all of the hooks 10 against disengagement from the supporting members with which they are connected a locking bar 12 is passed 100 downwardly between the web 4 and the adjacent inner side of the end 2 of the box. This bar 12 may be of any suitable material and in practice may conveniently be of paper board having an upper 105 section 13 turned at right angles, as shown. When entered back of the web 4, as shown in Fig. 3, it prevents movement of the hooks 10 so that the same cannot accidentally disengage therefrom. With the 110 cover 3 in closed position, as shown in Fig. 3, the locking bar 12 cannot be moved and the

garment hangers are securely connected with the supporting channel member as is evident. But when the box has reached its destination and is opened the locking bar 12 5 may be easily removed, whereupon the hooks 10 of the garment hangers may be readily disconnected from the sheet metal channel support with which they have been engaged.

The box may be of a length such as to 10 carry clothes at one end only thereof or, as shown in Fig. 4, it may be increased somewhat in length so that the clothes may be placed in both ends overlapping each other, each end of the box being equipped with 15 the construction shown in Fig. 1 for connecting the garment hangers securely in place.

In Figs. 5 and 6 the same invention is shown of a form which will permit the use 20 of the so-called round suspension hooks of garment hangers. In such case the web 4 is formed with an inwardly pressed concave midsection 4^a in which the slots 7^a are cut, the supporting members 8^a being formed with the curve of the concave section 4^a so as 25 to receive the curved or rounded hooks 10^a of the garment hangers. The loop or eye 11 at the end of the hook in such case becomes of value as the ends of the same strike against the web 4^a at one end of the 30 slots 7^a so that the hook 10^a cannot follow around the curved supporting portion 8^a and disengage therefrom. In order to disengage a hook 10^a from its supporting portion 8^a it is necessary to give the garment 35 hanger a movement to the left (referring to Fig. 5) which will turn the hook 10^a in a clockwise direction moving the terminal eye 11 away from the web 4. The same locking bar 12 with its upper end 13 is 40 used with this construction. It is, however, to be understood that with certain yieldable materials used in making shipping boxes it is possible to construct the sheet metal channel member so as to bring the 45 web 4 closer to the end 2 of the box and insert the suspension hooks for the garment hangers into place by pressing the same against the end of the box which will yield sufficiently to permit the same being hooked 50 over the parts 8 or 8^a. This can be done with boxes made of paper board in which case the locking bar 12 will not be needed. My invention comprehends making the 55 structure either with or without the locking bar 12 as may be thought best. This construction of shipping case and support for garment hangers on which garments are placed, is very strong and durable and may be economically produced. The invention is 60 defined in the appended claims and is to be considered comprehensive of all forms of structure coming within their scope.

I claim:

1. In combination with a receptacle having 65 an end, a member attached to the inner

side of said end of the receptacle having a web and flanges extending inwardly toward said end of the receptacle whereby the web is spaced from the end of the receptacle, said web having a plurality of slots cut 70 therein, means extending from one edge of each of said slots with which a garment hanger hook may engage, and a locking member slidably received between said web and the end of the receptacle to lock the 75 garment hanger hook against disengagement.

2. In combination with a receptacle having an end, a sheet metal member including a web paralleling and spaced a distance from the end of the receptacle, means permanently 80 securing said sheet metal member to the end of the receptacle, said web having a plurality of spaced apart transverse slots cut 85 therein, the metal at one edge of each slot struck from the web in making the slots being formed into a garment hook supporting portion, and a locking bar slidably received between said web and the adjacent inner side of the end of the receptacle.

3. In combination with a receptacle having an end, a sheet metal member secured to the inner side of the end of the receptacle having a web spaced a short distance from said end of the receptacle and flanges extending from the edges of the web to the end of the receptacle, said web having a plurality of slots cut at spaced apart points in and transversely of the web, and the metal at one edge of each of said slots being 95 formed into a hook support.

4. A shipping case or receptacle having a bottom, sides, ends and a movable closure top combined with means secured to an end of the receptacle with which garment hanger hooks may have detachable engagement, and a locking bar removably associated with said means for holding the hooks against disengagement, said locking bar being held against disconnection by the closure of the 100 receptacle.

5. In combination with a receptacle having a bottom, sides, ends and a movable closure top, of a channel shaped member of sheet metal secured in each end of the receptacle, the webs of said members being provided with spaced apart transverse slots and with a hook support located at each slot, a locking bar slidably received in each of said channel members between the webs thereof 115 and the adjacent end of the receptacle, said bar being formed at its upper end with a section turned at right angles to the body of the bar whereby when the closure top to the receptacle is in closed position it engages against said section and holds it and the attached locking bar against movement.

6. In a device of the class described, a flat member, a sheet metal member of channel form attached to one side of the flat member 120 having a web spaced a short distance from 125

the adjacent side of said flat member, said web being provided with a plurality of spaced apart transverse slots, a support for a hook located at one edge of each slot, and 5 a locking bar slidably received between the web and said flat member, substantially as described.

7. In a shipping case or receptacle having an end, a sheet metal member of substantially 10 channel form attached to the inner side of said end, said sheet metal member including a web spaced from the end of the receptacle and flanges extending from the web to the end of the receptacle, said web 15 being formed with a longitudinal concave depression and having a plurality of slots cut transversely therein, metal struck from the web in cutting said slots being formed into a concave support for a rounded hook, 20 substantially as described.

8. A construction containing the elements in combination defined in claim 7, combined with garment hangers having rounded hooks engaged with said supports therefor, each of the hooks of the garment hangers terminating in an eye adapted to engage against an adjacent portion of the said web. 25

9. A construction containing the elements in combination defined in claim 7, combined with a plurality of garment hangers having 30 rounded hooks engaged with said hook supports, each of said garment hanger hooks terminating in an eye adapted to bear against the web, and a locking bar slidably received in the channel member between said 35 hooks and the adjacent end of the receptacle.

In testimony whereof I affix my signature.

WALTER H. BATTS.
